DISPLAY DEVICE

Donald H. King, Chicago, Ill., assignor to Household Finance Corporation, Chicago, Ill., a corporation of Delaware

Application April 25, 1941, Serial No. 390,381

9 Claims.

(Cl. 40—12)

This invention relates to display devices, and has for its object to provide a new and improved display or advertising card structure.

More specifically stated, it is an object of the invention to provide an improved display or advertising device wherein a principal advertising or display card has associated therewith a series of smaller circulars or the like, adapted to be individually removed or disassociated from the principal card structure.

The invention contemplates improved means for removably associating the circulars with the principal card structure.

Further objects of the invention are to provide, in a structure of the foregoing type, new and improved means for facilitating the loading of the circulars upon the principal structure, and new and improved means for facilitating the individual removal of the circulars, one at a time, while the remaining circulars are maintained and retained in proper position.

Various objects, advantages and features of the invention will be apparent from the following specification when taken in connection with the accompanying drawing wherein a preferred embodiment is set forth for purposes of illustration.

In the drawing, wherein like reference numerals refer to like parts throughout:

Fig. 1 is a general assembly view of a display or advertising panel adapted to receive a card structure constructed in accordance with the principles of the invention:

Fig. 2 is a partial perspective view, on an enlarged scale, of the card structure, but showing it prior to bending and assembly upon the panel;

Fig. 3 is a view of the card, similar to Fig. 2, and showing it after assembly upon the panel and with the circulars in the retention pocket;

Figs. 4 and 5 are illustrative sectional views, on a further enlarged scale, showing the manner of operation of the pocket structure upon bending of the card;

Fig. 6 is an enlarged sectional view of the card with the circulars in assembled position, and taken on the line 6—6 of Fig. 3;

Fig. 7 is an illustrative perspective view of one of the circulars; and

Fig. 8 is a detail view more particularly illustrating the shaping of the retention pocket slot.

Referring more particularly to the drawing, in Fig. 1 there is illustrated a panel, generally indicated by the numeral 10 of a type and kind adapted to receive display or advertising card structures constructed in accordance with the invention. As shown, the panel is of the type usually associated with vehicles such as busses,

street cars, and the like. It is to be understood, however, that the invention is applicable to display or advertising devices generally, and that the panel or support structure accordingly may be mounted in various types of installations.

More specifically, referring to Figs. 1 and 3, the panel structure includes an elongated sheet metal support 11, curved in cross section, and provided at its opposite edges with inturned retention flanges 12 and 13. A single support 11 is adapted to receive a plurality of advertising or display cards, and to this end retaining bars 14 are provided at suitable intervals, adapted to engage the end edges of the cards and retain them in position against the surface of the support 11. The side edges of the cards are retained within the flanges 12 and 13, these flanges thus cooperating with the bars 14 to retain the cards firmly against the curved surface of the support 11. The bars 14 are formed of spring stock and may be removably engaged with the flanges 12 and 13 and snapped into card retaining position as shown in Figs. 1 and 3. By removal of the bars the cards may be interchanged and replaced.

25 The card structure, as constructed in accordance with the invention, is illustrated in perspective detail in Fig. 2, the card being shown in its normal flat condition prior to assembly upon the support structure. The card structure comprises, more specifically, a main card member 18 and a reinforcing or backing element 19, preferably arranged in one corner thereof, as illustrated. The backing element may be adhesively secured over its entire area to the rear face of the card. A die-cut slot, generally indicated by the numeral 20, is perforated through both the main card and the reinforcing element. The provision of the backing element enables the main card 18, preferably of cardboard or the like, to be made of sufficiently light stock so that it may be easily handled and snapped into position against the curved support structure 11. At the same time the backing element produces an area of increased strength and rigidity in the vicinity of the slot 20, the backing element, which may also preferably be of cardboard or the like, in effect producing a card of double thickness in the vicinity of the slot.

50 The particular shaping of the slot, constituting an important feature of the invention in one of its aspects, is more particularly illustrated in Fig. 8 of the drawing. As shown, the slot comprises a generally horizontal portion 21, and a pair of downwardly extending end portions 22 and 23, the end and horizontal portions cooper-

ating to form an inverted generally U-shaped slot structure. While the slot portion 21 is generally horizontally disposed, it will be noted that it is not truly horizontal, but is curved slightly, or sloped downwardly towards the ends. Also, it will be noted that the horizontal slot is of progressively increasing width towards its central portion. The end slot elements 22 and 23 extend downwardly and slightly toward each other at their lowermost ends. Also, the lower ends of these slot elements are rounded or provided with arcuate terminal surfaces. The particular shaping of the slot is of importance in effecting the objects of the invention, and its manner of operation, and cooperation with the other elements of the structure, is best illustrated in Figs. 4, 5 and 6 of the drawing.

Referring to the illustrative views, Figs. 4 and 5, and first to Fig. 4, this view shows the card and backing element in section, and illustrates the positions which the card areas in the vicinity of the slot tend to assume as the card is bent into generally arcuate or curved shape, corresponding to the curvature it will have when in assembled operative position. It will be noted that the card portion 24 disposed below the horizontal slot portion 21 and between the end slots 22 and 23 will not tend to assume a curved position, but on the contrary will remain substantially straight as the card is bent. The card portion 24, being unconnected from the upper card body by reason of the presence of the slot 21, and also being somewhat structurally divorced from the adjacent side card areas and the bending forces therein by reason of the presence of the slots 22 and 23, in effect forms a somewhat free tab element. Accordingly as the card structure is applied to its support 11, as illustrated in Fig. 5, the tab or card portion 24, while being forced to assume a partially bent or curved position, does not assume the same curvature or contour as the main card body. The tab assumes a lesser curvature and produces moreover at its upper portion 25, and particularly adjacent the center thereof as indicated at 25' in Fig. 8, an area of increased pressure against the support 11, and at its lower portion 26, an area of decreased pressure. Upon the proper proportioning of the parts for a given installation, the card portion 26 will separate itself slightly from the support structure 11, as indicated in Fig. 5, and in any event sections of decreased pressure, as indicated at 26' in Fig. 8, are provided to facilitate the introduction of circulars or the like into the slot structure.

It will be seen that the slot 21, when taken together with the card and the backing support 11, in effect forms a pocket structure into which circulars or the like may be inserted, and held in position between the card and the support. The position assumed by the parts upon the insertion of such circulars is illustrated in Fig. 6. As shown, a packet of circulars generally indicated by the numeral 30 is inserted so that their lower ends 31 are arranged within the pocket, and held in position between the card and the support 11, whereas the upper ends 32 of the circulars project outwardly from the pocket so as to be accessible for withdrawal, as indicated in Fig. 3. The circulars may be individual sheets, and one is illustrated in detail in Fig. 7. It will be seen that the circular comprises a main body portion 35 and a bent tab portion 36 adapted to extend downwardly and forwardly when the circular is in assembled position upon the card. The hori-

zontal length of the slot 21 is slightly greater than the width of the circulars, as illustrated in Fig. 3.

In operation the circulars are inserted as a packet or group into the pocket structure, and are thereafter removable individually by means of the extending tabs 36, as illustrated in Fig. 3. Due to the fact that the circulars are individual sheets, the supply within the pocket may be replenished at any time to the desired number, without removal or destruction of the remaining circulars such as would be necessary if the circulars were in book form or the like. As has been hereinbefore brought out, the areas of reduced pressure 26' provide convenient entry points for the lowermost corners of the circulars, facilitating their introduction into the slot and pocket structure. Moreover, the generally curved shape of the horizontal slot portion 21 permits the packet of circulars to be bent slightly as indicated by the dotted lines 37 in Fig. 7, upon insertion. This bending of the circulars imparts rigidity to the packet, facilitating its introduction into the slot and into the card pocket structure. While the circulars are held in the pocket, the curved shaping of the slot portion 21 still tends to impart a very slight curvature to the circulars aiding in retaining them in upright position. The circular extending tab portion 36 invites and facilitates the ready withdrawal of a circular, and at the same time discourages the removal of more than a single circular at a time. The pocket structure, including the action of the resilient retaining tab 24, as heretofore described, and the general clamping action afforded between the reinforced card and the backing support 11, permits the withdrawal of one circular without the disarraying or disturbing of the remaining circulars in the pocket. The backing element 19 provides for increased strength of the card structure in the vicinity of the pocket, and the location of the slot 20 in proximity to the retention flange 13 and the bar 14 permits these elements to impart the necessary supporting and retaining action to the pocket structure. In other words, the proximity of the support devices 13 and 14 to the pocket structure enables their supporting and retaining action to be imparted to the pocket, without causing the supporting forces to be transmitted through extended card surfaces such as would be true if the pocket were more centrally disposed on the card.

The curved or arcuate surfaces at the lowermost extremities of the slots 22 and 23 prevent tearing of the card and add durability to the construction.

It is obvious that various changes may be made in the specific embodiment set forth without departing from the spirit of the invention. The invention is accordingly not to be limited to the precise embodiment shown and described, but only as indicated in the following claims.

The invention is hereby claimed as follows:

1. A display device comprising a display card for mounting upon a support structure having a generally curved concave surface, said display card being held in concave curved position against the support structure and against the concave curved surface thereof when in mounted position on the support structure, said card having a slot formed therein whereby to provide a pocket between the card and the support structure surface, said slot when the card is in mounted position on the support structure having a central portion extending in the direction of the

generatrix of the curved support surface, and a pair of transversely extending end portions at each end of the central portion, to provide a free tab card portion resiliently engageable with the curved surface of said support structure.

2. A display device comprising a display card for mounting upon a support structure having a generally curved concave surface, said display card being held in concave curved position against the support structure and against the concave curved surface thereof when in mounted position on the support structure, said card having a slot formed therein whereby to provide a pocket between the card and the support structure surface, said slot being formed with portions extending substantially parallel to the generatrix of the curved surface and with juxtaposed portions extending angularly thereto whereby to provide one portion of the card within the pocket area having pressure engagement against the curved support surface, and another card portion along said slot being spaced slightly from said support surface when the card is in mounted position thereon.

3. A display device comprising a display card for mounting upon a support structure having a generally curved concave surface, said display card being held in concave curved position against the support structure and against the concave curved surface thereof when in mounted position on the support structure, said card having a tab forming slot formed therein whereby to provide a pocket between the card and the support structure surface, a portion of said card within the pocket area having a concave curvature less than the concave curvature of said curved support surface whereby to form one pocket card portion having increased pressure engagement against said curved support surface, and another pocket card portion having decreased pressure engagement against said curved support surface when the card is in mounted position thereon.

4. A display device comprising a support structure having a generally horizontally extending support surface, said support surface being concavely curved in vertical cross section, a display card, and means engaging the peripheral edges of said card to hold the card against the sup-

port structure and against the support concave surface thereof, said card having a tab forming slot formed therein adjacent one marginal edge thereof in the vicinity of said holding means whereby to provide a pocket between the card and the support structure surface, a portion of the card within the pocket area being of decreased concave curvature with respect to the concave curvature of the adjacent support surface whereby to provide a card portion within the pocket area having resilient pressure engagement against the support surface.

5. A display device as set forth in claim 4 wherein said card slot is provided with a generally horizontally extending central portion and vertically extending portions at each end of the central portion.

6. A support structure having a concave curved surface, a display card held against the concave surface and having an inverted U-shaped slot therein to provide a pocket between the card and support structure, with the central portion of the slot extending substantially parallel to the generatrix of the curved surface, and to provide a portion of the card within the pocket area having pressure engagement against the support structure surface.

7. A display device as defined in claim 1 wherein in the terminal extremities of each of said end portions are arcuately shaped.

8. A display device as defined in claim 1 wherein in the central portion and the end portions of said slot are shaped into a generally U-shaped, continuously curved slot structure.

9. A display device comprising a display card for mounting upon a support structure having a concave support surface, said display card being held against the support structure and against the concave support surface thereof when in mounted position, said card having a slot formed therein whereby to provide a pocket between the card and the support structure surface, said slot being of inverted U-shape with the central portion of the slot extending substantially horizontally when the card is in mounted position whereby to provide a card pocket portion having resilient pressure engagement against the support.

CERTIFICATE OF CORRECTION.

Patent No. 2,363,186.

November 21, 1944.

DONALD H. KING.

It is hereby certified that error appears in the printed specification of the above numbered patent requiring correction as follows: Page 3, second column, line 1, claim 4, for "support concave" read --concave support--; and that the said Letters Patent should be read with this correction therein that the same may conform to the record of the case in the Patent Office.

Signed and sealed this 27th day of March, A. D. 1945.

Leslie Frazer
